(57) **CLAIM**

The ornamental design for a room, as shown and described.

DESCRIPTION

FIG. 1 is a front outer perspective view of a room showing our new design;

FIG. 2 is a front inner elevation view thereof;

FIG. 3 is a rear inner elevation view thereof;

FIG. 4 is a right side inner elevation view thereof;

FIG. 5 is a left side inner elevation view thereof;

FIG. 6 is a top inner elevation view thereof;

FIG. 7 is a bottom inner elevation view thereof;

FIG. 8 is a front outer perspective view thereof showing the room in an environment in which it may be used;

FIG. 9 is a rear outer elevation view thereof;

FIG. 10 is a left side outer elevation view thereof;

FIG. 11 is a right side outer elevation view thereof;

FIG. 12 is a top outer elevation view thereof; and,

FIG. 13 is a bottom outer elevation view thereof.

The dashed broken lines in the Figures show portions of the room or elements thereof, or environment, that form no part of the claimed design.

The dot-dash broken lines in the figures show boundaries that form no part of the claimed design.

The oblique shade lines in the Figures show transparency or translucency.

1 Claim, 10 Drawing Sheets
